United States Patent Office

Des. 207,160
Patented Mar. 7, 1967

207,160

TIRE

Glen L. Wittenmyer, Akron, Ohio, assignor to The B. F. Goodrich Company, New York, N.Y., a corporation of New York

Filed Sept. 6, 1966, Ser. No. 3,748

Term of patent 14 years

(Cl. D90—20)

The figure is a perspective view of a tire showing my new design.

The dominant features of the design reside in those portions shown in full lines.

I claim:

The ornamental design for a tire, substantially as shown and described.
